UNITED STATES PATENT OFFICE.

IRA DUCKWORTH, OF FORT SMITH, ARKANSAS.

CORN-PAD.

SPECIFICATION forming part of Letters Patent No. 707,089, dated August 19, 1902.

Application filed May 23, 1901. Serial No. 61,612. (No model.)

To all whom it may concern:

Be it known that I, IRA DUCKWORTH, a citizen of the United States, residing at Fort Smith, in the county of Sebastian and State of Arkansas, have invented a new and useful Corn-Pad, of which the following is a specification.

This invention relates to shields or pads for protecting and curing corns, bunions, and similar affections; and the object of the same is to provide a device of this class with an outer flat rim of a thickened construction to surround the margin of the corn or bunion and an interior cavity to receive the projection of the latter, the cavity having a thin top closure in the form of a flat horizontal web without vertical projection above the plane of the top of the pad to prevent inward pressure of the web by contact with a portion of a shoe or stocking against the corn or bunion.

The invention consists in the construction and arrangement of the several parts, which will be more fully hereinafter described and claimed.

25 In the drawings, Figure 1 is a perspective view of a foot with one of the improved pads or shields applied to one of the toes thereof. Fig. 2 is a transverse vertical section of the pad.

30 Similar numerals of reference are employed to indicate corresponding parts in both views.

The numeral 1 designates the head of the pad or shield, which is formed with a cavity 2, opening through the bottom thereof and 35 having an upward and inward incline or a frusto-conical shape, the surrounding rim 3 being flat and transversely thicker at the base of the head, so as to provide a broad bearing-surface and a protection around the margin 40 of the corn or bunion, the upper portion of the said cavity having a top closure 7 in the form of a thin horizontal or flat web without vertical projection above the plane of the top of the head of the pad. The inwardly-inclined wall 4 of the cavity provides for a conformity to the shape of the projecting portion of the corn or bunion, and the flat thickened rim 3 will permit a comparatively large surface of the pad to rest upon the unaffected

45 50 flesh around the corn or bunion, and no part of the pad or shield comes in contact with the affected part. The comparatively extended surface, therefore, around the cavity distrib-

utes the pressure over so large a surface of the unaffected part of the flesh around the 55 corn or bunion that little or no danger exists of abrasion taking place from any pressure to which the device may be subjected by a boot or shoe. This is an important advantage in construction, as the flesh immediately around 60 the corn or bunion is generally tender and easily affected and would be very liable to become sore and abraded by any form of pad bearing upon a contracted surface of the flesh.

In treating corns or bunions it is necessary 65 in order to effect a cure that the affected parts shall be kept free from pressure, so that the natural recuperative forces may have free opportunity for action, and the improved pad or shield efficiently accomplishes this result, 70 while at the same time not affecting the tender and frequently inflamed flesh in the immediate neighborhood of the corn or bunion. Another important requirement is that the pad be held immovably in place while worn 75 by the patient, and for this purpose an elastic strap 6 is integrally formed with the head 1 and produces a firm binding on the toe over which it is placed and prevents lateral movement of the head, but is at the same time sufficiently yieldable to permit the free natural action of the toes or other parts of the foot to which it is applied.

The pads and their elastic supporting straps will be made in various sizes to fit different- 85 sized toes or to fit bunions or other similar affections.

Having thus described the invention, what is claimed as new is—

A corn-shield comprising a head having a 90 recess formed on its inner face and walls gradually reduced in thickness from the bottom toward the top thereof, the outer face of said walls being smooth and unbroken, said recess having the walls thereof converging to- 95 ward the top of said head, a thin covering extending over the top of said recess, and means for holding said head in adjusted position.

In testimony that I claim the foregoing as my own I have hereto affixed my signature in 100 the presence of two witnesses.

IRA DUCKWORTH.
